UNITED STATES PATENT OFFICE.

CHARLES H. HOWARD, OF SAUGUS, AND LEWIS SHARP, OF NORTH ATTLEBORO, MASSACHUSETTS, ASSIGNORS TO PAPER PRODUCTS MACHINE COMPANY, OF BOSTON, MASSACHUSETTS, A CORPORATION OF MASSACHUSETTS.

FABRIC OR PAPER REENFORCING MACHINE.

Application filed August 16, 1922. Serial No. 582,166.

To all whom it may concern:

Be it known that we, CHARLES H. HOWARD and LEWIS SHARP, a citizen of the United States and a subject of King George V of Great Britain, respectively, residing at Saugus, county of Essex, and North Attleboro, county of Bristol, and State of Massachusetts, respectively, have invented an Improvement in Fabric or Paper Reenforcing Machines, of which the following description, in connection with the accompanying drawings, is a specification, like characters on the drawings representing like parts.

This invention relates to machines for reinforcing fabrics with filaments, and more particularly to means for drawing rovings from a source of supply and forming the filaments in a sheet for application to the fabric to be reinforced.

It has been proposed heretofore to reinforce fabric such as paper by securing a sheet of unspun fibres adhesively to the fabric, and the unspun fibres used for this purpose are usually of long staple, such for example as sisal, flax, ramie and hemp.

The unspun fibres are usually prepared in roving or sliver form. That is, the fibres are reclaimed from the woody material or other undesirable foreign substance, which

naturally adheres to them, and are then formed into long, untwisted ropings, rovings, or slivers, the latter terms being variously applied, according to either the character of the fibres or the colloquial use. The

term "roving" will hereinafter be used to designate these untwisted ropings of fibre, and while the term will have more particularly in view such ropings of fibres of long staple, it is to be understood that the mechanism of the present invention may be used in connection with rovings formed of either long or short fibres or of a mixture of long and short fibres.

One of the problems presented in applying the fibres of rovings to the fabric to be reinforced, is the difficulty experienced in laying the fibres in an economically thin sheet, and in parallel relation on the fabric to be reinforced. It has been found, however, that by feeding rovings or moving them from a source of supply and then arranging them in sheet form, the fibres may be adhesively secured to the surface of the fabric in substantially parallel relation to

reinforce the fabric. To insure that the fibres of roving shall be distributed with substantial equality throughout the width of the fabric or paper to be reinforced, the fibres of the rovings are flattened or made into a sheet-like form, and then the sheet of fibres is attenuated and the fibres adhesively secured to the surface of the fabric or paper in substantial parallelism, and in many cases, while they are under longitudinal pull or tension.

In accordance with the present invention, a number of rovings are placed side by side in substantially parallel rows forming a sheet of rovings that is moved toward the fabric or paper to be reinforced. The supply of rovings may be drawn from coils or containers of the type in which rovings are commonly coiled, but these coils or containers occupy considerable space as compared with the size of the roving drawn therefrom, and since a large number of rovings may be required to form a sheet of fibres of the desired width, the arrangement of the coils or containers, and the means by which the individual rovings are led from the coils or containers to their place in the sheet of rovings, are important.

Furthermore, since the rovings are formed of unspun fibres they may pull apart as they are drawn forward unless provisions are made for maintaining the fibres forming the individual rovings in intimate frictional engagement with each other, so that the fibres of a roving will not slip readily lengthwise of each other.

An important feature of the present invention, therefore, consists of means for maintaining the untwisted fibres of a roving in intimate frictional engagement with each other so that a substantial pull may be exerted upon the roving to advance it without pulling the roving apart.

A more specific feature of the invention consists of spools, rolls or other roving engaging means arranged in spaced relation alternately above and below the rovings for forcing the individual fibres of the rovings in intimate frictional engagement with each other so that the draft or pull upon the rovings will not pull the fibres apart.

Another important feature of the invention, consists of means for directing rovings from their sources of supply, that may be

distributed over a relatively large area, along approaching paths into substantially parallel rows forming a sheet of rovings.

Since the coils or containers occupy considerable space, difficulty may be experienced in finding room for them in the vicinity of the reenforcing machine. Another important feature of the invention, therefore, consists of means whereby the 10 rovings may be formed into a sheet at a point remote from the paper reenforcing machine or upon another floor of a building, and may be drawn therefrom to the re-enforcing machine without breaking or 15 drawing out the rovings.

The above and other features of the invention and novel combination of parts will be herein described in connection with the accompanying drawings which show one 20 good, practical form of the invention.

In the drawings:—

Fig. 1 is a side elevation with parts shown in section of a paper reenforcing machine having the reenforcing filaments 25 supplied thereto in accordance with the present invention:

Fig. 2 is a plan view of means for directing the rovings from the source of supply into position to form a sheet;

Fig. 3 is an enlarged perspective view of 30 one of the directing means shown in Fig. 2;

Fig. 4 is an end view, looking to the left, of the structure shown in Fig. 3; and

Fig. 5 is an enlarged perspective view of 35 the left-hand half of the structure shown in Fig. 2.

Referring more particularly to Fig. 1: The reenforcing machine therein disclosed has a suitable supporting frame 10, at one 40 end of which are provided spaced uprights 11 which support the lower and upper rolls 12 and 13 respectively. These rolls may be fluted as shown, and one may be adjusted relative to the other by the hand wheels 14.

The sheet of filaments 15, which is formed 45 in a manner to be described, passes between the fluted rolls 12 and 13 and the flutes of the rolls grip the sheet and exert a pulling force upon the same. As the sheet leaves

50 these rolls it may be somewhat creased from the effect of the interengaging flutes, and the creases thus formed are removed by passing the sheet upwardly over the spreader bar 16 and then downwardly under the guide bar 17. The guide bar 17 serves to hold the

sheet 15 in position to be engaged by the teeth 18 of the upper run of the combs 19.

These combs preferably travel in an orbital path, and in the embodiment shown are secured to endless chains 20 passing around sprocket wheels 21, 22. Movement is imparted to the comb by a gear 23 driven by a worm 24 mounted on a shaft 25 shown as extending downwardly from overhead driving 60 means.

The combs 19 preferably are operated at a speed considerably in excess of the speed at which the sheet 15 is fed forward by the fluted rolls, and as a result, the teeth of the comb are drawn through the fibres of the sheet to straighten and attenuate the fibres. 70

The means for feeding the fabric or paper to which the reenforcing filaments are applied may be supported upon the frame 10, and in the construction shown, the sheet of 75 filaments 15 is introduced between two sheets of paper 26 and 27. The upper sheet 26 may be drawn from a roll 28 rotatably supported by uprights 29, and the lower sheet may be drawn from a roll 30. The upper sheet 26 passes about a guide roll 31 and then between the feed rolls 32 and 33, and the lower sheet 27 passes over the guide rolls 34 and 35, between a pair of rolls 36 and 37, one of which rotates in a receptacle 38 containing adhesive, and then about the feed roll 33 and between the feed rolls 32 and 33. 80

The sheet of filaments 15 is led from the combs 19 to the nip of the feed rolls 32, 33, 90 where it is introduced between the sheets of paper 26 and 27, and the two sheets of paper with the filaments therebetween are adhesively secured together by the adhesive applied to the inner face of the sheet 27. To insure that the sheets be firmly pressed together they may be led upwardly about the feed roll 32 and between the upper face of this roll and the roller 39, it then passes part way around the roll 39 and is led therefrom as a two-ply reinforced sheet 40. 95

The feed rolls 32 and 33 preferably are operated at a speed considerably in excess of the speed with which the sheet of filaments or fibres are advanced by the combs 19, with the result that the filaments are further drawn out or attenuated as they are gripped and drawn forward by the paper passing between the rolls 32, 33. A depressor 41 in the form of a reel may be positioned above the combs 19 at one end of their upper run to maintain the sheet 15 in engagement with the combs throughout the length of the upper run. 100

The construction of Fig. 1 is more fully described and is claimed in the co-pending application of Charles H. Howard and Lewis Sharp, Serial No. 391,433, filed June 24, 1920; and since the present invention relates more particularly to the construction of Figs. 2 to 5 inclusive, a further description of Fig. 1 is believed to be unnecessary herein. 115

As stated, the reenforcing filaments or fibres preferably are supplied in the form of rovings, and desirable means for drawing these rovings from a source of supply and arranging them side-by-side to form a sheet will now be described. A separate container is preferably provided for each supply of roving, and since these containers 120

are bulky, and a relatively large number of rovings may be required to form a sheet of the desired width, the roving containers will occupy considerable space. The present invention therefore contemplates a plurality of roving-carriers or guideways constructed and arranged to guide the roving from the source of supply along approaching or converging paths into substantially parallel rows forming the sheet 15.

The roving-carriers or guideways may be variously constructed and arranged, and in the embodiment shown six roving-carriers 42, 43, 44, 45, 46 and 47 are shown and each serves to guide a group of rovings toward the sheet formed by the several groups. The arrangement of the roving-carriers relative to each other may depend largely upon the disposition of the space available for the roving containers, and in Fig. 2 the roving-carriers are arranged in opposite pairs (see 42 and 47, 43 and 46, 44 and 45).

A frame for supporting the rovings as they are formed into the sheet 15 is preferably provided, and this frame may consist of side bars 48 and 49 supported a desired distance above the floor 50 (see Fig. 5) by uprights 51. Extending between the side bars 48, 49 are provided a plurality of rollers or guides 52. The delivery ends of the roving-carriers 42 to 47 inclusive may rest upon the side bars 48 and 49 while the other ends of the roving-carriers may be supported by depending rods 53 (see Fig. 3) adapted to support the carriers above the containers for the rovings. The several roving-carriers may be similar in construction and may consist of spaced side rails 54 and 55, the latter of which is arranged at an inclination to the former as shown. This is desirable because the number of rovings conducted by a carrier preferably increases toward the delivery end of the carrier. In the construction shown two rovings 56 are led upwardly from the containers or other source of supply at the narrow end of the carrier, and additional rovings are led upwardly to the carrier at spaced intervals along the length of the carrier into engagement with spools, rollers or guides to be described.

As stated, the rovings are formed of un-twisted filaments or fibres which will pull apart if the individual fibres are not maintained in intimate engagement with each other when the rovings are subjected to a longitudinal pull. It is therefore important to provide means for maintaining the fibres of the rovings in close frictional engagement with each other throughout the portions of the rovings that are subjected to a substantial draft or pull. To this end, in the embodiment of the invention shown, each of the roving-carriers is provided with a plu-

rality of grooved spools 57 arranged in spaced relation along the carriers, and it will be noted that the first two spools 57 have but two grooves apiece, while the next two spools have three grooves apiece to accommodate a third roving; thus the grooves of the spools increase toward the delivery end of the carrier. These spools are supported to rotate freely, and as will be apparent from Fig. 3, the rovings are led over one spool and under the next spool throughout the length of the carrier. This serves to force the opposite sides of the rovings into firm engagement with the spools and the pressure of the rovings upon each spool forces the individual fibres of each roving into intimate frictional engagement with each other, and it should be noted that this frictional engagement between the fibres increases as the draft or pull upon the rovings increases. As a result, the strength of the rovings increases with the increase in the draft upon the same, due to the increase in the frictional engagement between the fibres. The spools serve also to guide the rovings along their path of travel. The distance between any two spools 57 should not exceed the average length of the fibres of the rovings and preferably is considerably less than the average length of the fibres, with the result that the feeding pull upon the rovings will be imparted from one spool to the other by the individual fibres extending between two spools without pulling the rovings in two. Since, as above stated, the increase in the tension of the rovings passing alternately above and below the spools serves to increase the strength of the un-twisted rovings by forcing the fibres into intimate frictional engagement with each other, it is not essential that the spools rotate, for if they do not rotate the roving will slide over the same in a satisfactory manner.

A board 58 may be supported below the roving-carriers by posts 59 so that the edges of this board will guide the rovings upward into the proper grooves of the spools, and additional boards 60 and 61 (see Fig. 4) may be provided to further guide the rovings upwardly. The spool 57 at the delivery end of each roving carrier, in the construction shown, is arranged at an angle to the other spools and the angle preferably is such that as the rovings leave this spool they will be brought into contacting parallel relation as shown. The delivery ends of the carriers are arranged in stepped relation as clearly shown in Fig. 2, so that the group of rovings delivered by one carrier will be delivered alongside the group delivered by the next carrier. As will be apparent from Figs. 2 and 5, it is unnecessary to provide a roving-carrier for the central group of rovings since these may be led up-

wardly from the containers 62 over the rollers 52, and a guide board 62 provided with apertures 64 serves to guide the rovings to the rollers. The guide board 63 may 5 be supported by the cross braces 65 of the frame.

The groups of rovings delivered by the different carriers preferably are passed over one roller 52 and under the next, as shown, 10 to maintain the rovings in their proper position side by side and to produce the desired frictional engagement between the fibres forming the respective rovings, and after the several groups of rovings have been 15 positioned side by side to form the sheet 15, this sheet is led to the fluted rolls 12 and 13. The roving-supporting frame and associated carriers shown in Fig. 2 may be located adjacent the receiving end of the 20 machine shown in Fig. 1, or if desired, the mechanism of Fig. 2 may be located upon the floor 50 above the machine of Fig. 2. The latter arrangement is shown in the drawings, and in many cases is to be desired, because of the saving in floor space 25 upon the lower floor. In the present case the sheet 15 is led downwardly through an opening 66 in the floor 50 and is guided from the frame shown in Fig. 2 to the machine of Fig. 1 by a plurality of rollers 67 30 supported by uprights 68. The arrangement of the rollers 52 and 67, like that of the spools 57, is preferably such that the distance between adjacent rollers does not 35 exceed the average length of the fibres of the rovings, and the sheet 15 passes about one side of one roller and about the opposite side of the next roller. The arrangement is such that the fluted feed rollers 12 40 and 13 serve to draw the roving forward from the containers 62 upon the floor above, and the rollers and spools serve to produce sufficient frictional engagement between the individual fibres of the rovings to prevent 45 the rovings from being pulled apart by the feeding draft or pull to which they are subjected. The means for producing sufficient frictional engagement between the individual fibres of the untwisted rovings to 50 prevent the rovings from being pulled apart by the feeding pull to which they are subjected may be given various embodiments without departing from the scope of the invention as defined by the claims.

55 What is claimed is:—

1. A device for drawing rovings of unspun fibres from a source of supply, comprising in combination, means for pulling fibres in the form of rovings from a source 60 of supply, spools between the source of supply and pulling means and arranged to have the rovings drawn alternately over one spool and under the next in a zigzag manner so that the pull upon the rovings forces 65 the rovings against the spools and increases

the frictional engagement between the individual fibres of the rovings.

2. A device for drawing rovings of unspun fibres from a source of supply, comprising in combination, means for pulling 70 fibres in the form of rovings from a source of supply, transversely extending guides disposed along the path of travel of the rovings and arranged to have the rovings drawn alternately over and under the 75 guides in a zigzag manner so that the pull upon the rovings draws them against the guides to increase the frictional engagement between the individual fibres of the rovings.

3. A device for drawing rovings of unspun fibres from a source of supply, comprising in combination, means for pulling rovings from a remote source of supply, and means for maintaining the individual 85 fibres of the portions of the rovings that are under tension in intimate frictional engagement with each other, comprising guides disposed along the path of travel of the rovings and arranged to have the 90 rovings drawn alternately over and under the guides in a zigzag manner so that the tension of the rovings forces them against the guides.

4. A device for drawing rovings of unspun fibres from a source of supply, comprising in combination, means for pulling rovings from a remote source of supply, and guides disposed along the path of travel 95 of the rovings and arranged to engage the opposite sides of the rovings at intervals and to deflect the rovings from a straight line so that the tension of the rovings forces the opposite sides of the rovings against the guides to increase the 100 friction between the individual fibres forming the rovings.

5. A machine for forming rovings into a sheet of fibres, comprising in combination, means for pulling rovings from a 105 source of supply, carriers for directing the rovings from their source of supply along approaching paths into substantially parallel rows forming a sheet, and guides upon the carriers disposed along the path of travel 110 of the rovings and arranged to have the rovings drawn alternately over and under the guides to force the rovings against the guides and thereby increase the 115 friction between the individual fibres 120 forming the rovings.

6. A machine for forming rovings into a sheet of fibres, comprising in combination, means for pulling rovings from a 125 source of supply, and guides for directing the rovings from their source of supply along converging paths into parallel relation forming a sheet and arranged to have the rovings drawn alternately over and under the guides to force the rovings 130

against the guides and thereby increase the friction between the individual fibres forming the rovings.

7. A machine for forming rovings into a sheet of fibres, comprising in combination, means for pulling rovings from a source of supply, guides for directing the rovings from their source of supply along converging paths into parallel relation forming a sheet and arranged to have the rovings drawn alternately over and under the guides to force the rovings against the guides and thereby increase the friction between the individual fibres forming the rovings, and means for attenuating the fibres into a thin sheet.

8. A machine for forming rovings into a sheet of filaments, comprising in combination means for pulling filaments in the form of rovings from a source of supply, rollers spaced apart a distance less than the maximum length of the filaments of the rovings and disposed alternately above and below the rovings to force the individual filaments into frictional engagement with each other to thereby increase the friction between the individual filaments of the rovings throughout the length of the rovings to the source of supply, and means for directing the rovings into contacting parallel relation forming a sheet.

9. A machine for forming rovings into a sheet of fibres, comprising in combination, means for pulling fibres in the form of rovings from a source of supply, and rollers that are free to rotate to facilitate the advance of the rovings along their path of travel and arranged to have the rovings drawn alternately over and under the rollers so that the pressure of the rovings against the rollers serves to hold the individual fibres of the roving in intimate frictional engagement with each other.

10. A device for drawing rovings of unspun fibres from a source of supply, comprising in combination, means for pulling fibres in the form of rovings from a source of supply, spaced rollers supported along the path of travel of the rovings and arranged to have the rovings drawn alternately over and under the rollers so that a pull upon the rovings forces them against the rollers to increase the frictional engagement between the individual fibres of the rovings, and rounded grooves formed in the rollers to receive the rovings and constructed to prevent the fibres of the rovings from spreading out laterally.

11. A device for drawing rovings of unspun fibres from a source of supply, comprising in combination, means for pulling

fibres in the form of rovings from a source of supply, spaced rollers disposed along the path of travel of the rovings and arranged to have the rovings drawn alternately over and under the rollers so that the tension of the rovings holds them against the rollers to increase the frictional engagement between the fibres of the rovings, and grooves formed in the rollers for spacing the rovings apart and guiding them along their path of travel.

12. A machine for forming rovings into a sheet of fibres, comprising in combination, means for pulling fibres in the form of rovings from a source of supply, guides for directing the rovings along converging paths into parallel relation to form a sheet and arranged to engage the opposite sides of the rovings at intervals along their path of travel and to deflect the rovings from a straight line so that the tension of the rovings forces the opposite sides of the rovings against the guides to increase the friction between the individual fibres forming the rovings.

13. A machine for forming rovings into a sheet of fibres, comprising in combination, means for pulling fibres in the form of rovings from a source of supply in one portion of a building downwardly through the floor of the building to feeding means below, spaced guides positioned to guide the fabric downwardly through the floor of the building to said feeding means and arranged to engage the opposite sides of the rovings at intervals to deflect the rovings from a straight line so that the tension of the rovings forces the opposite sides of the rovings against the guides to increase the friction between the individual fibres forming the rovings.

14. A machine for forming rovings into a sheet of fibres, comprising in combination, means for pulling fibres in the form of rovings from a source of supply in one portion of a building downwardly through the floor of the building to feeding means below, spaced guides disposed along the path of travel of the rovings to guide them toward the feeding means and arranged to have the rovings drawn alternately about opposite sides of the guides in a zigzag manner so that the tension of the rovings forces them against the guides to increase the frictional engagement between the individual fibres of the rovings.

In testimony whereof, we have signed our names to this specification.

CHARLES H. HOWARD.
LEWIS SHARP.
